COIN SWITCH

John J. Toolan and Alfred E. Reiman, Chicago,
Ill., assignors, by mesne assignments, to Rock-
Ola Manufacturing Corporation, Chicago, Ill.,
a corporation of Delaware

Application June 12, 1946, Serial No. 676,182

2 Claims. (Cl. 194—9)

1

This invention relates in general to electric switches, and more particularly to improvements in coin operated switches.

In practically any type of installation in which a coin operated switch is employed, it will be subjected to abuse by some of the users of the equipment with which it is associated, and attempts will be made to cause its operation by jarring or shaking, as by the application of sharp blows to the switch housing or casing enclosing the same.

A principal object of the instant invention, therefore, is the provision of an electric coin switch which is operable only by a particular type of coin properly deposited, and which is not operable by jarring or shaking or by forces applied exteriorly to its enclosing and supporting structure.

Another important object of the invention is to provide such a switch which nevertheless will be actuated in positive manner by a coin of the particular denomination for which it is designed, without impeding travel of the coin therewith.

A further important object of the invention is the provision in a coin operated switch of means normally operable to retain the switch in open position and to resist closing thereof, except in response to the action of a particular type of coin properly deposited, which means also functions, after the deposit of such a coin, to close the switch and to maintain the same closed.

Another object of the invention is the provision of such a switch in which the proper application of only a minimum weight is necessary to release such means for closing the switch, while said means at the same time functions to apply a maximum closing pressure to the contacts of the switch.

A further object of the invention is to provide solenoid means in such a switch which, when energized, opens the switch and reconditions the means which was holding the switch closed to perform its other function of retaining the switch in open position and resisting any attempted closing thereof except that resulting from the deposit of a proper coin.

Another object of this invention is the provision of such a switch in which the solenoid means for opening the switch is electrically connected in series with the switch contacts, and wherein the contacts are therefore so constructed and arranged as to maintain the flow of current to energize said solenoid switch opening means until the latter has overcome the switch closing function of the means which normally maintains the switch in open position.

2

Numerous other objects and advantages of the invention will be apparent as it is better understood from the following description, which, when taken in connection with the accompanying drawings, discloses a preferred embodiment thereof.

In the drawings:

Fig. 1 is a vertical elevation of a wall box or remote control unit for an automatic phonograph, with parts broken away to show a coin operated switch embodying the features of the instant invention mounted therein;

Fig. 2 is an elevational view of the switch of Fig. 1 in closed position;

Fig. 3 is a detail elevation illustrating the path of travel taken by the free end of the coin operated lever of the switch;

Fig. 4 is a horizontal sectional view taken substantially on the line 4—4 of Fig. 2; and

Fig. 5 is a vertical elevation similar to Fig. 2, with parts broken away, and showing the switch in open position.

Referring more particularly to the drawings, a coin operated switch embodying the features of this invention is designated generally in Fig. 1 by reference numeral 11, and is illustrated therein as comprising part of a wall box or remote control unit 12 which also includes a plurality of selector buttons or keys 13, record identifying indices 14 respectively associated with each of the selector keys, a coin receiving slot or coin chute 15, and a coin mechanism or slug rejector 16 of any one of the types commonly in use for detecting and rejecting spurious coins deposited in the coin chute 15 and delivering genuine coins of the proper denomination to a coin receiving slot 17 (Figs. 2 and 4) forming a part of the switch 11. The wall box 12 is intended for use as a remote control actuating mechanism for an automatic phonograph in similar manner to that illustrated in U. S. Letters Patent No. 2,389,327, issued November 20, 1945, but it will be understood that the switch 11 may be used with any other type of coin controlled mechanism desired.

The switch assembly 11 comprises a main supporting plate 18 having a substantially U-shaped guide plate 19 secured in any suitable manner to the rear face thereof to define therewith the open-ended coin receiving chute or slot 17. A horizontally disposed stud shaft 21 extends forwardly through a suitable aperture in the supporting plate 18 and is riveted or otherwise suitably secured at its rear end thereto. Pivottally mounted on the stud shaft 21, by means of an

elongated hub 22, is a link 23 which is secured in any desired manner to the hub and extends downwardly below the supporting plate 18. The outer or forward end of the hub 22 is held against axial movement on the shaft 21 by a split washer or keeper 24 mounted in a suitable annular groove in the shaft. At its lower end, the link 23 carries a stud 25 upon which the lower portion of a two-armed lever 26 is pivotally mounted, the lever being spaced forwardly from the link 23 by a washer 27 mounted on the stud 25 (Fig. 4).

The longer arm of the lever 26 terminates at its outer end in a rearwardly extending finger or coin-actuated pawl 28 which passes freely through aligned slots 29 in the supporting plate 18 and 31 in the guide plate 19 (Fig. 4), so as to be disposed in the coin receiving slot 17 in the path of movement of any coin delivered to the latter by the slug rejector 16. A coil spring 32 is connected at its lower end to the lever 26 between its pivotal connection to the stud 25 and the finger 28, and is connected at its upper end to a horizontally disposed shelf or retaining bracket 33 formed integrally with and bent forwardly from the supporting plate 18. It will be noted from the drawings that the point of attachment of the lower end of spring 32 to lever 26 is spaced horizontally to one side (to the right in Figs. 2 and 5) of the link supporting shaft 21, and that the point at which the upper end of the spring is anchored to the shelf 33 is spaced from shaft 21 on the other side or to the left thereof, for a purpose which later will be more fully apparent. Relative movement between the lever 26 and link 23 is limited by a pin 34 carried by the link 23 and extending forwardly through an aperture 35 in the lever 26.

The shorter arm of the lever 26 is bent horizontally and forwardly from the main body thereof to provide a shelf 36 to which is riveted a contact holder or supporting plate 37 of any suitable non-conducting material. Riveted to the under surface of the non-conducting holder 37 and having its outer edge flush with the outer or left-hand edge thereof is a movable contact plate 38. An angularly disposed contact holder or supporting plate 39 of suitable non-conducting material is riveted at its upper edge to a shelf 41 bent forwardly from, and formed integrally with, a solenoid supporting bracket 42 which, in turn, is attached to the main plate 18. A stationary contact plate 43 is riveted to the upper surface of the holder 39, with the lower edges of these two members being flush with each other.

The bracket 42 is also provided with a forwardly extending shelf 44 for supporting a solenoid 45 and, together with the shelf 33, retaining the solenoid fixed in desired position, wherein the lower end of the plunger 46 of the solenoid is in operative relationship with the contact holder 37 carried by the lever 26. A bracket 47 which, if desired, may be secured to the supporting plate 18 by one of the screws employed to attach the solenoid bracket 42 thereto, carries a strip 48 of suitable non-conducting material upon which are mounted terminal members 49 and 51. A lead or wire 52, comprising one side of the circuit involved, is soldered or otherwise suitably secured to the stationary contact plate 43. The movable contact plate 38 is electrically connected by a lead 53 to the lower terminal 51 which, in turn, is connected by a lead 54 to one side of the solenoid coil 45. The other side of the solenoid 45 is connected by a lead 55 to the upper terminal 49, to which is also connected a lead 56 (Fig. 1).

comprising the other side of this local switch circuit.

As has been noted hereinbefore, the coin switch 11 above described is adapted to initiate the operation of any desired coin controlled mechanism, upon presentation of a suitable coin to the receiving slot 17, by closing the normally open circuit between the leads 52 and 56. In the embodiment of the invention herein illustrated, the switch 11 is shown incorporated in the remote control unit 12 of an automatic phonograph similar to that disclosed in U. S. Letters Patent No. 2,389,327. In the operation of such a phonograph, it is not only necessary that a proper coin be deposited to initiate a playing cycle, but also it is desirable that a selection be made of a particular record to be played by operation of one of the selector buttons 13. Consequently, a normally open selector switch is provided (not shown herein) to which the lead 56 is connected and which is closed by operation of any one of the selector buttons 13. This switch corresponds to the switch 324 in said Patent No. 2,389,327. With this arrangement, deposit of a proper coin closes the normally open switch 11, in a manner to be described in detail hereinafter, and subsequent actuation of any selector button 13 completes the circuit through the switch 11 (by closing the selector switch corresponding to switch 324 of said patent), so that operation of the phonograph mechanism controlled by the unit 12 is properly initiated. Such completion of the circuit between leads 52 and 56 also energizes the coil of solenoid 45 to cause delayed opening of the switch 11, in a manner to be described in detail hereinafter, and restoration of the switch 11 to its normally open position. It will be understood, of course, that this sequence of operation of the switch 11 and any selector button 13 may be reversed, if the usual latching mechanism is incorporated in the unit 12 for retaining any selector button in depressed position until selection in the phonograph of the record identified thereby has been accomplished. However, since it is intended that the switch 11 may be employed to initiate operation of any desired coin controlled mechanism, such phonograph mechanism is not illustrated herein, and reference is made to said Patent No. 2,389,327 for a complete disclosure thereof. It will also be readily understood that the lead 52 and the lead 56, or the opposite side of the selector switch controlled by the buttons 13 and to which lead 56 is connected, are connected, respectively, in well-known manner to the opposite sides of a suitable source of electrical energy, not illustrated herein, for energizing the coil of solenoid 45 when contact plate 38 is in engagement with contact plate 43.

The switch 11 is illustrated in its normally open position in Figs. 1 and 5, wherein the movable contact holder 37 is held in engagement with the lower edge of the stationary contact holder 39 by the spring 32, and the finger 28 of the lever 26 is retained in engagement with the upper ends of the slots 29 and 31. The application of force to the lever 26 by the spring 32 is sufficient to prevent any movement of the lever by jarring or shaking, as by forces applied from the exterior to the supporting plate 18. Due to the pivotal connection of the lever 26 and link 23, however, the weight of a coin against the finger 28 of the lever is sufficient to overcome this retaining function of the spring 32. Coins deposited in the slot 15 will travel through the slug rejector 16 in well-known manner, the func-

tion of the latter being to eliminate spurious coins and to deliver to the coin receiving slot 17 only genuine coins of the proper denomination. As illustrated in Fig. 2, such properly delivered coins will encounter the finger 28 to move the lever 26 downwardly. The path of movement of the finger 28 is illustrated in Fig. 3 by the broken line 57, the outer or right hand portion of which shows the movement imparted thereto by a coin passing through the receiving slot 17. Since the outer end of the receiving slot 17 is cut away or open, the coin falls outwardly therefrom as illustrated in Fig. 2, releasing the lever 26 for return movement by the spring 32. During this downward movement of the lever 26, the stationary contact holder 39 initially functions as an additional pivot for the lever and the movable contact holder 37 slides up and over the lower edge thereof. At the same time, the weight of the coin on the finger 28 is such as to cause the initial downward movement of the lever 26 to be about its pivot 25 and relative to the link 23, as limited by the pin 34 extending through the aperture 35, and thereafter to be about the pivot provided by the stud shaft 21. As soon as the finger 28 is released by virtue of the coin falling therefrom and out of the receiving slot 17, the spring 32 swings the lever 26 and link 23 to the left and the finger 28 upwardly in a combined motion about the pivots 25 and 21 to the intermediate position shown in full lines in Fig. 2. The two extreme positions of the lever 26, comprising its uppermost or normal position of Fig. 5, and its lowermost position, are illustrated in broken lines in Fig. 2. In the intermediate position shown in full lines in Fig. 2 to which the lever 26 is moved by the spring 32 upon release of the finger 28 by a coin passing through the slot 17, the movable contact plate 38 is engaged with the stationary contact plate 43 to close the local switch circuit from the lead 52 through the leads 53, 54, 55 and 56. In this position, the spring 32 maintains a firm contact between the plates 43 and 38. Since there has been no current in this local switch circuit during the above described movement of the lever 26 from its position of Fig. 5 to that of Fig. 2, the plunger 46 of the solenoid 45 has been resting freely upon the movable contact holder 37 and is therefore carried upwardly to its position of Fig. 2.

Closing of the local circuit as above described will have no immediate effect in the control unit herein illustrated until, or unless, one of the selector buttons 13 has been depressed. Such actuation of a selector button 13, as previously noted, will close the selector switch to which the lead 56 is attached so that the coil of the solenoid 45 will be energized. It will, of course, be understood that in other installations than that herein illustrated, the circuit involved may comprise only the leads 52 to 56, with the leads 52 and 56 directly connected to the coin controlled mechanism with which the switch is associated. In any event, the coil of the solenoid 45 is connected in series with the switch contacts 38, 43.

Energization of the coil of the solenoid 45 causes the plunger 46 thereof to be moved downwardly in well-known manner from its position of Fig. 2 to that of Fig. 5. During the initial portion of such movement, the movable contact plate 38 will be slid along the upper surface of the stationary contact plate 43, moving the lever 26 downwardly and to the right, the finger 28 thereof taking the path of movement illustrated in Fig. 3 by the toothed portion of the broken

line 57. During such movement of the lever 26 by the plunger 46 of the solenoid, the local circuit through the solenoid will thus be maintained by the contact plates 38 and 43 to enable the solenoid to perform its function of releasing the movable contact 38 and its supporting plate 37 from the stationary contact plate 43. At this point the circuit will be broken and the solenoid 45 deenergized. During such releasing movement, the lever 26 has been moved in a clockwise direction about the pivot 25 relative to the link 23. Immediately upon release of the movable contact plate 38 from the stationary contact 43, the spring 32 functions to return the lever 26 relative to the link 23 and to move the latter in a clockwise direction about its pivot 21 to bring the parts back to their normal position of Fig. 5, wherein the movable contact holder 37 rests against the lower edge of the stationary contact holder 39 and the finger 28 engages the upper ends of the slots 29 and 31.

From the above description, it will be seen that the spring 32 normally functions to retain the switch in open position by maintaining the parts in their position of Figs. 1 and 5 and resists any attempt to close the same except in response to the action of a particular type of coin properly presented to the receiving slot 17. At the same time, only a minimum weight needs to be applied to the finger 28 to overcome this function of the spring 32 and to so reposition the parts of the switch mechanism as to enable the spring 32 to then function to apply a maximum closing pressure to the contacts of the switch. The resulting energization of the solenoid 45 overcomes this closing pressure of the spring 32 and moves the parts of the switch mechanism until the movable contact has been disengaged from the stationary contact, which movement also reconditions the spring 32 to again perform its other or normal function of retaining the switch in open position and resisting any attempted closing thereof, except that resulting from the deposit of a proper coin.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. A coin switch, comprising a pair of relatively movable contacts, a stationary non-conducting member supporting one of said contacts and having one edge flush with an edge of said contact, a movable non-conducting member carrying the other said contact and having one edge flush with an edge of the latter and disposed in parallel relationship to said one edge of said stationary member, a supporting link pivotally mounted for movement normal to said parallel edges, a bell-crank lever pivotally mounted on said link for movement parallel thereto and having one arm supporting said movable member, a spring connected to a second arm of said lever for normally maintaining said edges of said non-conducting members in engagement with each other to prevent unauthorized engagement of said contacts with each other, the end of said second arm of said lever being operable by a coin against the action of said spring to disengage said edges of said members, and means for per-

mitting limited relative movement between said lever and said link to enable such coin-actuated disengagement of said edges of said members, said spring being automatically operable, following such disengagement and passage of the deposited coin out of engagement with said second arm, to close said switch by actuating said lever and said link to cause and resiliently maintain engagement between said contacts.

2. A coin switch according to claim 1, including a solenoid connected in series with said contacts and operable against said movable non-conducting member, when energized, to swing said lever relative to said link against the action of said spring to disengage said contacts and permit said spring to move said non-conducting members into normal engagement, such opening of the switch by said solenoid thereby automatically de-energizing the solenoid.
